UNITED STATES PATENT OFFICE

2,539,933

BEDRAIL EXTENSION DEVICE

I. Irving Silverman, Chicago, Ill., assignor to
Bechik Products, Inc., St. Paul, Minn., a corporation of Minnesota

Application February 14, 1947, Serial No. 728,473

7 Claims. (Cl. 5—296)

1

This invention relates generally to means whereby a normal size bedstead may be lengthened and more particularly to a device for extending the bed rail of the standard type bedstead.

The primary object of this invention is to provide a device which can be readily attached to a bed rail and which will thereby extend the length of said bed rail whereby the length of the entire bedstead will be increased making it possible to accommodate therein a person of tall stature.

Another object of the invention is to provide a simple device of the character described which will be simple and effective in operation and economical to manufacture.

Another object of the invention is to provide a device of the character described, which when associated with a bedstead will be substantially locked in position.

A further object of the invention is to provide a device of the character described which is capable of being adjusted for compensating for variations in the dimensions of standard bed rail connections made by various manufacturers.

Still a further object of the invention is to provide a device of the character described which will not only lengthen the bedstead, but which will cause the rails to be firmly connected with the posts thereof, and will also be capable of being adjusted to take up wear on the connecting members to prevent the connection from being loose.

Still other objects of the invention are to provide a device of the character described which is extremely simple to install.

With the foregoing and other objects in view which will appear as the description proceeds, the invention consists of certain novel features of construction, arrangement and a combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawing a preferred embodiment thereof, from an inspection of which, when considered in connection with the following description of my invention, its mode of construction, assembly and operation and many of its advantages should be readily understood and appreciated.

Referring to the drawing in which the same

2

characters of reference are employed to indicate corresponding or similar parts throughout the several figures of the drawing:

Fig. 1 is a perspective view showing a portion of a bedstead having my new invention associated therewith and showing the manner in which the bed rail is lengthened thereby.

Fig. 2 is a side elevational view of the same on an enlarged scale with portions broken away and others in section to show the details thereof.

Fig. 3 is a fragmentary plan elevational view of the device of Fig. 2 with portions broken away and shown in section.

Fig. 4 is a fragmentary sectional view taken generally along the line 4—4 of Fig. 2 and in the indicated direction.

The reference character 10 designates generally a bedstead comprising, for illustrative purposes, a head- or foot-board 11 having corner posts, one of which is shown at 12. A bed rail 13 is shown adapted to be connected with the post 12 and support thereon slats 14 or the like for supporting the spring and mattress (not shown). The rail 13 has its end provided with a metal blade member 15 of the conventional formation, having upper and lower hooks 16 and 17, respectively, and providing slanted slots 18 and 19. The post 12 is slotted as shown at 20 and carries pins 21 and 22 passing through the post and across the slot 20. The blade hooks 16 and 17 are adapted to cooperate with the post slot 20 in such a manner that the slots 18 and 19 will engage the transverse pins 21 and 22 respectively and thereby hold the bedstead in assembly.

It is sometimes desirable, where the bedstead is to be used by persons who are taller than usual, that the bedstead be longer than standard. The usual bedsteads are six feet long and will accommodate tall persons uncomfortably, and hence by means of my invention it is possible to increase the length of the bedstead considerably, whereby longer mattresses and springs may be installed, thereby accommodating such persons comfortably.

I provide a device 23 which is interposed between post 12 and bed rail 13 and having means for cooperating with the pins 21 and 22 as well as the blade 15 to retain the members in assembled relationship.

The device 23 comprises a shell 24 formed as a channel-shaped member having a side wall 25, top and bottom walls 26 and 27 and flanges 28 and 29 integrally formed with the same member and being disposed parallel to said wall 25. Slidably accommodated within the shell 24 there are

provided two slidable members, one of which may be termed the pin member 30 and the other of which may be termed the blade member 31. The pin member 30 is formed having a generally channel-shaped cross-section to conform with the inner cross-section of the shell 24. There is a side wall 32, top and bottom bearing flanges 33 and 34 and the flanges 35 and 36 parallel to the wall 32. The top flange wall 33 extends only partially along the width of the pin member 30 so that when the blade 15 is associated therewith in a manner to be described, the space or opening 37 permits passage thereof. Upper and lower pins 38 and 39 are riveted to the wall 32 for cooperation with the slots 18 and 19 of the blade 15. Centrally of the wall 32 is a lug 40 integrally formed therewith, said lug having a screw-threaded opening therein for accommodating therein the screw threaded end 41 of the double ended stud 42. The opposite end 43 of said stud is similarly associated with the lug 44 of the blade member 31. The pins 38 and 39 are each formed with a head portion, a reduced diameter portion 45 which will be firmly accommodated within the slots 18 and 19, and are riveted as shown at 46 to the wall 32.

The blade member 31 is also formed of channel-shaped cross-section, having the wall 47, upper flange wall 48, lower flange wall 49, upper flange 50, lower flange 51. An extension of the wall is bent at 52 to form a blade 53 having upper and lower hooks 54 and 55, and upper and lower slots 56 and 57.

When the device 23 is separate from the bedstead 10, the assembled blade and pin members 30 and 31 readily slide in the shell 24 and can be shipped separately. Since there is no mechanical connection between the shell 24 and the pin and blade members, the shells 24 can all be fabricated separately and the customer required to assemble same. Although the internal members must be made right and left the shells 24 are the same for a pair of such devices. Thus considerable saving is effected.

The device 23 is associated with a bedstead in the following manner:

First the blade member 31 is attached to the post 12, same having the stud 42 and pin member 30 connected therewith. Then the shell 24 is slipped over the blade and pin members with the open portion thereof facing inwardly of the bedstead and the slots 56 and 57 adjacent the bed rail 13. Next the hooks 16 and 17 are engaged upon the pins 38 and 39, respectively, in the process, the hook 16 passing through upper slot 53 in shell 24 and through the space or opening 37. When the device is thus assembled, the stud 42 is turned by means of a wrench, pulling the lugs 40 and 44, and hence the members 30 and 31 together. The device is thus tightly assembled and substantially locked in position. It will be found that the hook 16 is moved a sufficient distance to the right as viewed in the figures such that a major portion thereof extends beyond the extent of space 37 thereby providing means for preventing withdrawal of the device 23 in case of failure of pins 21 and 22 or loosening of blade member 15.

By slight variation of details, the open portion of the members 30 and 31 may be arranged to face away from wall 25 instead of towards it, thus exhibiting the whole of the stud and the blade member 15. The described embodiment, however is preferred.

It is believed that my invention, its mode of

construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. In a bed rail extension of the character described in which a pair of slidable members having hook and pin ends respectively are adapted to slide and be confined within a channel-shaped spacing member, means for enabling a bed rail hook to be engaged upon said pin end comprising a slot formed in the edge of said spacing member adjacent the end adapted to be secured to the bed rail, said slidable member having the pin end being substantially channel-shaped so as to enable same to slide within said spacing member and having a slot formed in an edge thereof adjacent the first mentioned slot to permit passage of said bed rail hook.

2. A bed rail extension device for operative disposal between one end of a bed rail having hooks and an adjacent bed post having pins; comprising a spacing shell, a member slidable within said shell and having pins for interlocking engagement with said bed rail hooks, a second member slidable within said shell and having hooks for interlocking engagement with said bedpost pins, and adjustable means interconnecting said slidable members.

3. The structure according to claim 2, wherein in said slidable members are of channel form in cross section and include vertical side walls and lugs extending inwardly from said side walls, and said adjustable means comprises a double-ended screw threadedly engaged with said lugs.

4. A bed rail extension device for operative disposal between one end of a bed rail having hooks and an adjacent bedpost having pins; comprising a spacing shell open at one side, a member slidable within said shell and having pins for interlocking engagement with said bed rail hooks, a second member slidable within said shell and having hooks for interlocking engagement with said bedpost pins, an adjustable connection between said members, and said shell being substantially channel-shaped in cross section with the slidable members and adjustable connection exposed at the open side of the shell.

5. The structure according to claim 4, wherein in said members are each of substantially channel-shape in cross-section, and said shell and members each include edge flanges cooperating to provide guided slidable movement of the members within the shell.

6. A bed rail extension device for operative disposal between one end of a bed rail having hooks and an adjacent bedpost having pins; comprising a spacing shell, a member slidable within said shell and having pins for interlocking engagement with said bed rail hooks, a second member slidable within said shell and having hooks for interlocking engagement with said bedpost pins, said shell including a vertical side wall having upper and lower channel-shaped flanges, and each of said members including a vertical wall having upper and lower flanges slidably disposed in the channels of the shell.

7. A bed rail extension device for operative disposal between one end of a bed rail having

outwardly projecting upper and lower hooks and an adjustable bed post having upper and lower hook engageable pins; comprising a spacing shell including a vertical side wall having upper and lower horizontal walls and vertical flanges and providing therewith guide channels at the upper and lower edges of the side wall, a pair of slidable members each including a vertical side wall and upper and lower horizontal walls and vertical flanges slidably disposed in the channels of said shell, one of said members having pins for interlocking engagement with said bed rail hooks, the other member having hooks for interlocking engagement with said bed post pins, and means adjustably connecting said members, the upper horizontal wall of the slidable pin carrying member being constructed to provide an elongated opening communicating with an elongated slot in the upper horizontal wall of the shell for receiving the upper bed rail hook when moving same into engagement with a pin of the pin carrying member, and said opening being shorter than the horizontal extent of said last mentioned hook for locking same into position on said pin in assembled adjusted relation.
